UNITED STATES PATENT OFFICE.

HARRY O. DAVIDSON AND OTTO HILLMAN, OF CLEVELAND, OHIO, ASSIGNORS TO THE HYDRAULIC PRESSED STEEL COMPANY, OF CLEVELAND, OHIO, A CORPORATION OF OHIO.

CONCRETE-FORM.

1,324,881.

Specification of Letters Patent. Patented Dec. 16, 1919.

Application filed March 29, 1917. Serial No. 153,202.

To all whom it may concern:

Be it known that we, HARRY O. DAVIDSON and OTTO HILLMAN, citizens of the United States, residing at Cleveland, in the county 5 of Cuyahoga and State of Ohio, have invented a certain new and useful Improvement in Concrete-Forms, of which the following is a full, clear, and exact description, reference being had to the accompanying drawings.

10 This invention relates to concrete mold forms, and particularly to internal forms for use in molding sewers, culverts, conduits and the like; and the invention has for its general objects the production of a form of 15 the foregoing nature which is collapsible; which is comparatively light and convenient of handling, and which is made up longitudinally of sections arranged to overlap or telescope within one another in the production 20 of a continuous mold form of the required length.

Further and more specific objects are the production of a concrete mold form of the above character which comprises flexible 25 segmental plates having longitudinal engaging edges that are turned inward sufficiently oblique to a line radial with respect to the plates to afford easy removal of the plates; to provide effectual retainers for alining and 30 supporting the form plates, the same being readily collapsible; and the provision of a device for clamping together and alining the adjacent edge portions of adjoining plates.

Constructions wherein the foregoing objects are attained are illustrated in the drawings accompanying and forming a part hereof, and wherein similar reference characters designate corresponding parts throughout the several views.

40 Figure 1 is a transverse section of the mold form, such section being taken on the line 1—1 of Fig. 2; Fig. 2 is a longitudinal section on the correspondingly numbered line of Fig. 1; Fig. 3 is a sectional detail 45 through the form adjacent the connected ends of a support or retainer; Figs. 4 and 5 are sections on the line 4—4 and 5—5 respectively, of Fig. 3; Fig. 6 is a horizontal section on the line 6—6 of Fig. 3; Fig. 7 is a 50 view, similar to Fig. 3 showing the couplers through which adjacent ends of adjoining sections of the support or retainer are connected; Fig. 8 is a horizontal section on the line 8—8 of Fig. 7; Fig. 9 is a perspective

view of the device for clamping and alining 55 adjacent edge portions of adjoining plates; Figs. 10 and 11 are elevations of the device, the views being taken at right angles to each other; and Fig. 12 is a transverse section through a mold form involving three seg- 60 mental sections.

The form plates are designated 1 and their longitudinal edge portions are turned in- 65 ward, as shown at 2, slightly oblique to a line radial with respect to the curvature of the plates to an extent and for a purpose which will presently be described. The extreme edges of these inturned portions are then turned over to produce flanges 3 which are substantially parallel to the adjacent body 70 portions of the plate. It has been said that the plates are flexible. The formation of their edge portions just described permits them to be readily disengaged from each other after the concrete hardens, the edge 75 portion of one of the plates forming an ob- tuse angle with its adjacent body portion, while the other forms a complementary acute angle the angular portion being such that the one of greater angle may be readily 80 withdrawn from engagement with the other by flexing the plate.

It has been stated above that the form 85 is divided longitudinally into sections, and that the ends of adjacent sections overlap or telescope one into the end of the other. This arrangement is dependent somewhat upon the flexibility of the plates for the reason that the end of one plate may be in- 90 serted into the end of another with its edge portions 2 fitting into the corresponding portions of the said other plate, and when the clamping devices and retainers are ap- 95 plied to the form the telescoping joint does not affect its accuracy of size or shape. It may be explained that the relative thickness 100 of the form plates and the size of the various clamping and retaining elements are somewhat exaggerated in the drawings for the obvious purpose of clearness of illustration. When the actual thickness of plates used in practice is compared with the size of the forms, which may be a number of feet in diameter, it will be seen that the surface of the form at the joint will be comparatively 105 smooth.

The adjacent edge portions of adjoining form plates are clamped together by the

device illustrated in detail in Figs. 9 to 11, the present embodiment consisting of opposed jaws 5 and 6, which have bearing heads 7 at one end and are pivoted together upon a bolt 8 at the other. The jaws are adapted to be drawn toward each other by a bolt 10 which passes through a transversely elongated opening 11 in the jaw 6, and the bolt is arranged to have the portion adjacent its head 12 contained within a notch 13 which opens through the side of a boss 14 of the jaw 5. The outer face of the boss is flat for engagement with the head of the bolt 10 and adjacent the open side of the notch, has lugs 15 which overhang the side of the head and prevent its turning when the wing nut 16 is manipulated upon the threaded end of the bolt for the purpose of drawing together or permitting the separation of the jaws. The notch affords ready removal of the headed end of the bolt upon a slight unscrewing of the wing nut sufficient to allow the head to pass the lugs 15 wherefore the clamp may be very quickly and easily applied to and disengaged from the edge portions of the plates. The bearing heads 7 are angularly disposed to the jaws so that when the clamp is applied to the oblique edge portions 2, it is substantially radially disposed with respect to the form.

Journaled upon the bolt 10 between the jaws is a cam 18 which is arranged to have its periphery swung into engagement with the flanges 3 of the form plates, and upon having its radially enlarged portion forced into contact with said flanges as it is rotated upon the bolt 10 by the blows of a hammer or other means, it forces the flanges, and consequently the body portions of adjoining plates, into proper relative positions—that is, until the outer surfaces of the plates are substantially flush. In this operation the bolt 10 acts as an abutment, fixed with respect to the jaws, and opposed to the flanges 3 and between which and the flanges the cam 18 is adapted to be wedged.

Thus the clamping device provides a very convenient means of securing the plates together, and properly alining them, which means is durable; comparatively simple and inexpensive of manufacture, and is readily operable under conditions prevailing in the construction of concrete masonry.

Form supports or retainers 20 are distributed along the form at suitable distances apart for holding the forms distended in proper shape and size. Each support or retainer comprises a plurality of segmental sections 21 that are pivotally connected throughout the circumference of the retainer by couplers 22, except where the ends of the retainer are temporarily connected by a coupler 23. It may be briefly explained before describing the retainer in detail that

it is made collapsible for the obvious purpose of facilitating its placement and removal; and since the shape of the form is practically determined by the retainer, it is essential that it be accurate in shape when 70 in use. To this end we provide means for forcing the adjacent ends of adjoining sections of the retainer into alinement and for effectually holding the parts in such position. Such means is required where the 75 retainer comprises more than three sections, for in cases where the retainer comprises three sections or less, there is no tendency for the parts to get out of alinement after the ends of the retainer are connected, as 80 will be further explained hereinafter. While we have shown a circular form in the drawings, it is obvious that the alining feature of the retainer would be of equal importance in forms of other shapes. 85

The coupler 23 through which the ends of the retainer may be connected is illustrated in detail in Figs. 3 to 6. The sections 21 are preferably T shaped in cross-section, and to one side of the central flange 90 of one end of the retainer is connected the upper end of an L-shaped plate 25, the plate being turned inward beneath and into the plane of the flange as shown particularly in Fig. 5. A smaller plate 26 is applied to 95 the opposite side of the flange and extends down over the adjacent portion of the plate 25 where it is connected to said plate by rivets 27. The plates 25 and 26 are secured to the opposite sides of the flange of the section 21 by rivets 28. Plates 30, similar in shape to the plate 25 but reversed as to position, are pivotally connected to the central flange of the opposite end of the retainer by a bolt 31, the plates being held in operative position by a pin 32 which passes through alining holes in the plates and flange. The plates being spaced apart a distance substantially equal to the thickness of the flange permits the end portion of the 100 plate 25 to enter between the corresponding portions of the plates 30, and these portions of the various plates have registering openings for the reception of a wedge 33 whereby the ends of the retainer may be forced 105 apart to expand the form to the accurate aggregate size of the plates 1. The fact that the plates 30 are pivoted to the retainer allows them after the pin 32 has been removed to be swung down out of the way of 110 the opposite end of the retainer when the same is collapsed.

The pivotal coupler 22 is illustrated in detail in Figs. 7 and 8 and comprises an entering plate 35 which is connected, with the smaller plate 36 to the central flange of the retainer by rivets 37. Correspondingly shaped plates 38 are connected, by the rivets 39, to the adjacent end of the adjoining section and these plates are adapted to receive 130

between their end portions the end portion of the plates 35, the overlapping portions of the plates 35 and 38 being pivotally connected by a bolt 40. The plates 38 are spaced 5 apart below the flange of the section 21 by a filler 41 that is held in place by the rivets 42. It will be observed that the outer ends of the plates 38 are extended to overlie considerable of the body portion of the plate 10 35, and the adjacent portions of these plates are provided with registering openings for the reception of a key 43 which is shown as wedge-shaped. It is by means of these keys that the parts may be forced into proper 15 relation to each other with the adjacent ends of the sections 21 in alinement, for it will be seen that if the key receiving openings are slightly out of alinement before the key is inserted, the driving of the key into the 20 openings will force the opening into absolute register, and with the other parts bearing the proper relation to the openings, they are bound to assume correct relation.

One of the adjacent ends of the adjoining 25 sections is cut away on an incline, as shown at 45, to permit it to pass the adjacent in-turned edge portions of the form plates; and it will be noted that the couplers are amply recessed for the accommodation of such portions.

In Fig. 12, we have shown a form in which the circumference is made up of but three segmental plates 1^a, and the retainer 20^a comprises a corresponding number of sections 35 which are pivoted together by couplers 22^a which are identical in every respect with the former couplers 22 except for the omission of the keys, for it will be recalled that in forms of three circumferential sections or 40 less, alinement devices for the retainer sections are unnecessary since, when the ends of the retainer are joined, it can assume nothing but a true circle (or other normal shape, whatever that may be).

45 We claim—

1. A form made up circumferentially of a plurality of interchangeable transversely curved flexible plates, the adjacent edges of adjoining plates being turned inward for 50 engagement with each other at an angle oblique to the radius of the plates.

2. A retainer for forms of the character set forth, said retainer comprising sections, and means pivotally connecting adjacent 55 ends of adjoining sections and including means by which said ends may be forced into and retained in proper relation to each other.

3. A retainer for forms of the character 60 set forth, said retainer being arranged to extend about the interior of the form, interfitting coupling members connected to the opposed ends of the retainer and offset laterally therefrom, said members having 65 wedge receiving openings and a wedge in-

sertible within said openings for expanding said retainer, one of said members being pivotally connected to the retainer.

4. A retainer for forms of the character set forth, said retainer being arranged to extend about the interior of the form, interfitting coupling members connected to the opposed ends of the retainer, said members having wedge receiving openings, a wedge insertible within said openings for expanding said retainer, one of said members being pivotally connected to the retainer, and means for securing the pivoted member in operative position.

5. A retainer for forms of the character set forth, said retainer comprising a plurality of sections, interfitting members attached to adjacent ends of the adjoining sections and offset laterally therefrom, means pivotally connecting said members and further means for forcing said members into proper angular relation to each other and for maintaining them in such condition.

6. A retainer for use with forms made up circumferentially of a plurality of plates, the adjacent edge portions of adjoining plates being turned inward for engagement with each other, said retainer comprising a plurality of sections corresponding in number to the number of plates in the form, each section being arranged to repose between the opposed inturned edge portions of a plate, interfitting members connected to adjacent ends of adjoining sections, means connecting 100 said members, the members being shaped to bridge over the inturned edge portions of the plates.

7. A retainer for use with forms made up circumferentially of a plurality of plates, the adjacent edge portions of adjoining plates being turned inward for engagement with each other, said retainer comprising a plurality of sections corresponding in number to the number of plates in the form, each 105 section being arranged to repose between the opposed inturned edge portions of a plate, and means connecting adjacent ends of adjoining sections, one of such ends being cut away to escape the inturned edge portions 110 of the plates as the retainer is collapsed.

8. The combination of form elements having adjacent edge portions turned laterally for engagement with each other, a device comprising means for clamping said 120 edge portions together and having an abutment opposed to said edge portions, and a member adapted to be wedged between said abutment and the said edge portions for forcing such portions into proper relation 125 to each other.

9. The combination of form elements having adjacent edge portions turned laterally for engagement with each other, a device comprising means for clamping said 130

- edge portions together, and a cam carried by said device for engagement with said edge portions for forcing them into proper relation to each other.
5. 10. The combination of form elements having adjacent edge portions turned laterally for engagement with each other, a device comprising a pair of jaws arranged to have clamped between them said portions, a 10 member extending transversely of the jaws, and a cam journaled upon said member for coöperation with the aforesaid edge portions for forcing said portions into proper relation to each other.
15. 11. The combination of form plates having adjacent edge portions turned laterally for engagement with each other, and a device comprising a pair of jaws arranged to have clamped between them said edge portions, a bolt for drawing said jaws toward each other, and a cam journaled upon the bolt for engagement with the aforesaid edge portions whereby said portions may be forced into proper relation to each other.
20. 12. The combination of form plates having adjacent edge portions turned laterally and then back over their respective body portions thereby to produce channels, and a device comprising opposed jaws having 30 parts for the occupancy of said channels,
- means for drawing said jaws toward each other, and further means incorporated within said device for forcing the edge portions into proper relation to each other.
13. The combination of form plates, having adjacent edge portions turned laterally and then back over their respective body portions thereby to produce channels, and a device comprising opposed jaws having parts for the occupancy of the said channels and means for drawing said jaws toward each other and including further means for forcing the edge portions into proper relation to each other.
14. A form made up circumferentially of a plurality of curved plates having their edge portions in engagement with each other, the engaging edge portions of the several plates being turned inward in a plane at an acute angle to the radius of the arc of the 50 plates.

In testimony whereof, we hereunto affix our signatures in the presence of two witnesses.

HARRY O. DAVIDSON.
OTTO HILLMAN.
